SASH WINDOW

Heinrich Thomas, Solingen-Wald, Germany

Application April 2, 1932, Serial No. 602,828, and
in Germany April 4, 1931

1 Claim. (Cl. 20—42)

This invention relates to a sash window, the lower sash of which lies in the closing position in the same plane with the upper sash. The invention consists in that the lower sash is guided by means of lateral pin-bars of U-shaped cross section, which are fixed from the lower edge of the lower sash up to the top edge of the same on elements hingedly mounted in and adapted to be turned down out of the window frame and extend as separate stationary connecting bars up to in front of the upper sash or the front guide bars of the same. Thus on the one hand the lower sash, after the turning down of the U-shaped guide bars can be freely turned over and on the other hand if well guided it can be shifted upwards in front of the upper sash.

An embodiment of the invention is illustrated by way of example in the accompanying drawing in which:

- 20 Fig. 1 is a front elevation of the window.
 Fig. 2 is a longitudinal section of Fig. 1.
 Fig. 3 is a section on line 3—3 of Fig. 1.
 a is the lower sash and b the upper sash. The upper sash b is guided vertically shiftable on the lower edge by laterally arranged stationary pins c and on the upper end by lateral shiftable pins d in grooves e in the side parts of the window frame. Corresponding to the front guide bars g of the window frame for the upper sash guide bars h are arranged in front of the lower sash a. These guide bars h are adapted to be secured in the inoperative position by means of latches f. On the inner edge of the guide bars h metal bars i of U-shaped cross section are arranged, which extend upwards as separate stationary bars. Pins k projecting from the lower sash engage in these U-shaped metal bars i. If, after the latches have been pulled up, the upper edge 40 of the lower sash a is moved forward the sash

can be shifted upwardly to in front of the upper sash b as the pins k of the lower sash a are guided in the curved U-shaped bars i to in front of the guide bars g of the upper sash. The upper sash b can then be moved downwards in being reliably guided by means of the pins c and d in the grooves e in the side parts of the window frame. In its lowered position the upper sash b can be turned over, the pins c serving as pivots. If the guide bars h are turned over from out of the window frame, after the latches f have been pulled back, the lower sash a can be freely turned over.

In order to ensure the lower sash a in the position in which its upper edge bears against the guide h or against the U-shaped metal bars i fixed thereon i. e. to prevent it from swinging back, hooks may be hingedly fixed on the upper edge of the lower sash a adapted to engage in the U-shaped metal bars i.

I claim:

A sash window the upper and lower sashes of which lie in the same plane when the window is closed, comprising in combination with the uprights of the window frame the upper sash, vertically shiftable in said frame and the lower sash, guide pieces hingedly connected at their lower end to the lower end of said uprights and extending to the top of said lower sash, guide bars of U-shaped cross section mounted on and extending to the upper edge of said guide pieces, lateral pins on the lower end of said lower sash engaging in said U-bars, and rigid extensions of said U-bars on the upper portion of said uprights adapted to cooperate with said U-bars to guide said lower lateral pins and prevent rattling of said bottom sash when being raised and lowered.

HEINR. THOMAS.
